UNITED STATES PATENT OFFICE.

STEPHEN M. SMITH, OF BOISE, IDAHO.

HAULING APPARATUS.

1,246,175.

Specification of Letters Patent. Patented Nov. 13, 1917.

Application filed March 15, 1917. Serial No. 155,068.

To all whom it may concern:

Be it known that I, STEPHEN M. SMITH, a citizen of the United States, residing at Boise, in the county of Ada and State of Idaho, have invented certain new and useful Improvements in Hauling Apparatus, of which the following is a specification.

This invention relates to hauling apparatus, and more particularly to apparatus adapted to be used in hauling or pulling one or more relatively large hawsers, where it is unpractical to perform this by hand, and also to form a convenient means of connecting one or more sources of power to a hawser.

One of the objects of the present invention is to provide a reliable and efficient apparatus of the above character, which may be easily and quickly applied to various sized hawsers for the purpose herein set forth. A further object is to provide a simple and practical apparatus of the above character which may be conveniently used in exerting power upon one or more hawsers, and connecting said hawsers to the source of power.

Other objects will be in part obvious from the annexed drawing, and in part indicated in connection therewith by the following analysis of this invention.

This invention accordingly consists in the features of construction, combination of parts and in the unique relations of the members and in the relative proportioning and disposition thereof, all as more completely outlined herein.

To enable others skilled in the art so fully to comprehend the underlying features thereof that they may embody the same by the numerous modifications in structure and relation contemplated by this invention, a drawing depicting a preferred form has been annexed as a part of this disclosure, and in such drawing, like characters of reference denote corresponding parts throughout all the views, in which—

Figure 1 is an elevational view of one of the attaching devices;

Fig. 2 is a transverse sectional view taken on line 2, 2 of Fig. 1;

Fig. 3 is a diagrammatic perspective view showing one application of the present invention, and

Fig. 4 is a detail perspective view of one of the parts of the attaching device.

Referring now to the drawing in detail, and particularly to Fig. 3, it may be noted by way of explanation that one or more relatively large hawsers 5 are adapted to be connected at one end with the object to be moved, while the opposite end, indicated at 6, is left free. A plurality of clamping or attaching devices, indicated at 7, are secured to the hawser, or hawsers, as the case may be, at desired intervals, and are connected by means of ropes 8, to housing drums or sources of power indicated at 10. These attaching or clamping devices 7 are so constructed as to firmly grip the hawser 5 when pull is exerted upon the ropes, yet when the strain is relieved and slack produced in the ropes 8 the clamping devices are free to be moved longitudinally toward the right, as shown in Fig. 1, thus to take a further bite, as it might be termed, upon the hawser, if occasions demand. In this way the tension on the several winding drums and associate cables 8 may be made substantially uniform, all slack being taken up, and when in this position or condition, the drums are simultaneously operated to exert a steady pull upon the hawser 5.

Each of these clamping devices, as shown more clearly in Fig. 1, comprises a plurality of pairs of plates 11, and two end pairs of plates 12 adapted to be secured at opposite sides of the cable or hawser 5, and securely held in place by means of connecting bolts 13 passing through perforated ears or lugs 14 upon each of the members. The holes in these lugs are of sufficient size to permit the bolts to pass freely therethrough, the ends of the bolts being provided with lock nuts 15, thereby to avoid any danger of the clamps becoming separated.

The inner surfaces of the plates 11 and 12 may be formed in any desired manner, but preferably with longitudinal spiral turns adapted to conform more or less to the strands of the cable to prevent slipping of the plates along the hawser when pull is exerted thereon.

Each of the plates 11 and 12 are provided with turned-up ears 16 at their sides through which the hauling cables 8 are woven, as

shown in Fig. 1, these hauling cables 8 being at both sides, as shown in Fig. 2, the ends being passed around the hawser 7, as indicated at the right of Fig. 1.

5 This method of winding the cables through the lugs or eyelets 16 is somewhat analogous to the lacing of a shoe, whereby as pull is exerted upon the ends of the cables 8, in a direction toward the left, the adjacent pairs 10 of clamping plates will be drawn toward each other to firmly grip the hawser therebetween. When the pull is released the clamping action will of course also be relieved and the plates tend to separate, thus 15 permitting the entire clamping device to be moved bodily toward the right. The plates 12 are provided with additional lugs or guard lugs 17, as shown in Fig. 4, to prevent accidental displacement of the hauling 20 cables.

The method of use and operation of a device of this character is substantially as follows:

The hawser 5, as shown in Fig. 3, is assumed to have its right-hand end attached to the object to be moved, with the left-hand end line free. The clamping devices are attached thereto by removing the bolts 13, as may be necessary, after which the bolts are 30 put in place and the nuts screwed on to the desired amount but insufficient to exert a clamping action upon the hawser. The hauling cables 8, after being given a turn around the hawser are woven back and forth 35 through the lugs 16, as shown in Fig. 1, and the ends attached to the winding drums, or other source of power 10. On rotating the drums a pull will be exerted upon the several hauling cables which causes the plates 12 to 40 clamp upon the hawser and transmit the pull thereto. After taking in a certain amount drums may be released, the hauling cables loosened, and the clamping device slid along 45 the hawser 5 to take a fresh bite thereon. This operation is repeated from time to time until the desired result is accomplished.

It is thus seen that the present invention provides a simple and practical hauling apparatus adapted to accomplish, among 50 others, all of the objects and advantages above set forth. It will also be seen that the apparatus can be employed to exert a pulling or hauling action on rope or wire cables or upon metal bars.

55 I realize that considerable variation is possible in the details of construction and arrangement of parts without departing from the spirit of my invention, and I therefore do not intend to limit myself to the specific 60 form shown and described.

Having thus described my invention what I claim as new and desire to secure by Letters Patent is:

1. In a hauling apparatus of the charac-

ter described in combination, a plurality of 65 pairs of curved plates adapted to be bolted together in pairs upon opposite sides of a hawser, and hauling ropes connected directly with the hawser and plates adapted to exert a clamping action of each pair of the plates 70 on the hawser when pull is exerted upon said hauling ropes.

2. In a hauling apparatus of the character described in combination, a plurality of 75 pairs of curved clamping plates mounted upon opposite sides of a hawser, bolts loosely connecting and holding said plates in position and hauling ropes wovenly connected with said plates and passing around the hawser adapted to cause a clamping action 80 of the plates upon the hawser when a pull is exerted upon said hauling ropes.

3. In a hauling apparatus of the character described in combination, a pair of clamping plates adapted to engage opposite sides of a 85 hawser, a hauling rope connected directly with the hawser and said plates adapted to cause said plates to clamp the hawser when said hauling ropes are pulled.

4. In a hauling apparatus of the character 90 described in combination, a pair of curved plates engaging opposite sides of a hawser, lugs at the sides of said plates, hauling ropes secured to the hawser and passing over said lugs in a manner to cause said plates 95 to move toward each other when said hauling ropes are pulled.

5. In a hauling apparatus of the character described in combination, a pair of curved plates engaging opposite sides of a hawser, 100 lugs at the sides of said plates, hauling ropes secured to the hawser and passing over said lugs in a manner to cause said plates to move toward each other when said hauling ropes are pulled, and bolts connecting said plates 105 at opposite sides of the hawser adapted to prevent removal thereof.

6. In a hauling apparatus of the character described in combination, a plurality of 110 curved plates having securing lugs at their ends, bolts passing freely through said lugs adapted to hold the plates in normal position, ears at each side of the lugs, and hauling ropes woven through said ears adapted to exert a clamping action of said plates 115 upon the hawser when said ropes are pulled.

7. In a hauling apparatus of the character described in combination, a plurality of 120 curved plates having securing lugs at their ends, bolts passing freely through said lugs adapted to hold the plates in normal position, ears at each side of the lugs, and hauling ropes woven through said ears adapted to exert a clamping action of said plates upon the hawser when said ropes are pulled, 125 the inner surfaces of said plates being provided with a roughened surface to prevent slipping of the plates along said rope.

8. In a hauling apparatus of the character described, a plurality of pairs of plates adapted to engage opposite sides of a hawser, each plate having a central perforated ear at 5 each end, fastening means connecting said ears at opposite sides of the hawser to prevent removal of the plates, hooks at each side of each ear, guard lugs having their open ends disposed at an angle to the longitudinal axis of the line of pull, and hauling ropes adapted to be given a turn about said

hawser and woven through said attaching hooks in a manner to cause said plates to move toward each other and clamp the hawser when the pull is exerted thereon. 15

In testimony whereof I affix my signature in presence of two witnesses.

STEPHEN M. SMITH.
